SAFETY COVER FOR MACHINERY

Harry Frederick Latham, Walton-on-Thames, England, assignor to Elliott Brothers (London) Limited, London, England, a company of Great Britain and Northern Ireland

Original application January 18, 1946, Serial No. 642,025. Divided and this application July 17, 1947, Serial No. 761,683. In Great Britain February 5, 1945

2 Claims. (Cl. 146—67)

1

This invention relates to safety covers for machinery, and more particularly for power driven apparatus for the mechanical treatment of food, and is applicable with advantage to so-called bowl cutting machines. In a preferred form of the invention, this machine and a mincer are arranged in a common frame. The invention has for its object to provide improved safety covers which while giving a large amount of safety, can be readily removed under safe conditions. Another object is to provide an improved safety cover which is relatively inexpensive to manufacture.

Other objects and features of the invention will be ascertained from the following description, by way of example, of a food-preparing machine incorporating the present invention. In the drawings Fig. 1 is a plan view of a combined bowl cutting machine and mincer, while Figs. 2 and 3 are sectional elevations on lines 2X—2X, and 3X—3X respectively, and Fig. 4 shows part of Fig. 3 at a larger scale.

Referring now to the drawings 1 is the common frame of the combined bowl cutting machine and mincer, and 2 is a bowl for the bowl cutting machine, which is supported by a ball bearing 3 for rotation about a vertical axis. 5 is the knife head which carries three knives 54, 55 and 56 of the bowl cutting machine and is adapted to rotate about a horizontal axis. Accidental access to the knife head 5 during the operation of the machine is prevented by a protective hood or safety cover 6. Under this safety cover 6, a comb 49 cooperates with the knives 54, 55 and 56 which pass through its slots. An electric motor (not shown) is provided to drive a main shaft 12 in the frame 1 of the machine, which serves to drive the knife spindle 51 through a belt drive 13 and also serves to rotate the bowl 2. A worm shaft 15 is driven by shaft 12 through belt drive 14 and carries a worm 16 meshing with a worm wheel 17, which, through a free-wheel device 35, drives the vertical shaft 18 which is mounted in a ball bearing 3, and which carries bowl 2. The cover 6 is pivoted about a hinge pin 31, which, according to the present invention, is permanently mounted in the cover 6. The stationary part of the hinge consists of a bracket 61 which is secured to the frame 1 of the machine. Slots 47 are provided in the bracket 61 to receive the hinge pin 31, and the comb 49 of the machine is provided with one or more extensions 63 which, when the comb is secured in its operative position, extend across the slot 47 and close it on top of the hinge pin 31 so as to prevent the hinge pin 31 from being

lifted out of the slot 47. The comb 49 with its extension 63 is held in position by a bolt 44 which passes through the comb 49 and has on its outer end a knob 45 suitably shaped for hand operation, 5 while a screw-threaded end 46 at its other end engages into a tapped hole provided in the bracket 61. Alternatively, the bolt 44 may be permanently screwed into the tapped hole in bracket 61, the knob 45 being in this case made as a nut 10 adapted to be screwed into the free end of the bolt 44. In either case it will be seen that when the comb 49 is secured in position by operation of the knob 45, it is impossible to remove the cover 6 from the bowl cutting machine without 15 first opening it by pivotal movement about its hinge, since the cover 6 when in its closed position prevents access to the knob 45. Suitable means, for example, such as will be described further on, are also provided to prevent opening of the cover 20 6 when the machine is in operation, while a short-stroke switch 34, for example a microswitch such as described in the specification of U. S. Patent 1,950,020, is preferably provided to prevent the machine from being put into operation 25 unless the hinge has been properly assembled and secured in position.

In the machine as illustrated, the switch 34 has a plunger 33 which when cover 6 is closed and knob 45 has been screwed down, is pressed back by 30 a projection 32 of the hinge pin 31 to close an electric circuit for the operation of the machine, while when knob 45 is partly or wholly unscrewed, the pressure of a return spring acting on plunger 33 will be sufficient to slightly lift the hinge pin 31 35 and thus break the circuit for the operation of the machine. The circuit will also be broken if the knob 45 remains in its loading position but cover 6 is opened by a movement about the hinge pin 31 since in this case the projection 32 on the hinge pin 31 will move along the groove indicated at 48 40 out of the path of the plunger 33, this plunger being thus allowed to move outwardly, thus again interrupting the electric circuit for the operation of the bowl cutting machine. Disposed laterally 45 of the bowl cutting machine, a feeding tray 7 is mounted on the frame 1 for a mincer which may be of the type described in the specification of British Letters Patent No. 512,805. It comprises a worm 8 in a chopper head 9 and is arranged underneath the tray 7, from which the food to be minced is supplied to the mincer through a chute 10. An electric motor 11 drives the mincer through suitable reducing gearing, enclosed in a gear box 57. During operation of the bowl cutting machine, the cover 6 of the machine is held

in position by a hand lever 19 (Fig. 1) which is provided with a tongue 20 normally preventing the cover from being opened. When, in order to permit opening of the cover 6, lever 19 is shifted to the position shown in chain-dotted lines, a drum 21 having a cut-off portion at 22 is rotated with the lever. A switch 23, preferably a micro-switch as described in the specification of U. S. Patent 1,950,020 or some other short-stroke switch, cooperates with drum 21 in such a manner that when lever 19 is moved out of the locking position, the recessed portion 22 of the drum 21 allows the plunger 24 of switch 23 to move into the circuit-breaking position of the switch. At the same time a steel band 25 passing over a pulley 26 to a weight 27 on a lever 28 is released by the rotation of drum 21, so that weight 27 will apply tension to a brake band 29 which acts on a brake drum 30 mounted on shaft 12. It will thus be evident that when lever 19 is moved to permit opening of the cover 6, the electric circuit for the motor driving the bowl cutting machine is interrupted by means of switch 23, while at the same time a brake 27, 28, 29 is applied to the drive of the bowl cutting machine, so as to prevent the knives 54, 55, 56 from being rotated and the bowl 2 from being driven. In view of the above-described arrangement of switch 34, it will further be evident that when cover 6 is opened by pivotal movement about the axis of pin 31 so as to permit access to the knives 54, 55, 56, projection 32 will move away from the plunger 33 thus allowing switch 34 to break the electric circuit for the motor drive of the knives 54, 55, 56 and bowl 2. The provision of this second circuit breaker in the circuit of the electric motor removes the danger that after opening of the cover 6, the driving motor may be put into operation again by returning handle 19 to the position as shown in full lines in Fig. 1. On the other hand, during cleaning of the knives it is desirable to turn handle 19 to this position so as to release the brake for the drive of the cutting knives and the bowl, thus permitting the knives and bowl to be moved by hand for convenient cleaning thereof. In order to facilitate manual rotation when it is desired to rotate the bowl faster than the rate at which it is mechanically driven, worm wheel 17 is rotatably mounted on the driving shaft 18 of the bowl, a free-wheel mechanism being provided between worm wheel 17 and a driving head 35, which latter is secured for common rotation with the shaft 18. The outside of frame 1 is provided with a sheet-metal or similar covering 36 which prevents accidental access to any part of the drive and injuries that might be caused thereby as well as preventing dust developing inside of the drive from contaminating food in the machine or elsewhere in the room containing it. A hinged table 37 is normally accommodated as shown in a recess provided in the metal covering 36 and can be tilted to the position in which it is shown in chain-dotted lines, in which it is adapted to carry a bowl for receiving the food which leaves the mincer 8, 9. Any suitable means may be employed for holding table 37 in its working position when required. The means shown in the drawing, merely by way of example, consist of a spring-biased locking pin 38 adapted to enter into a recess 39 provided in the hinge pin 40 for the table 37. Frame 1 rests on feet which are provided with rubber cushioning 41, one of the feet being provided with an adjustment spindle 42. By rotation of this spindle

a plate 43 which rests on the rubber cushioning 41 may be raised or lowered, this vertical adjustment serving to ensure a firm stand of the machine irrespective of the condition of the floor. It will be obvious that the machine as described may be varied in a number of details without departing from the scope of the present invention. This application is a division of patent application Serial No. 642,025, filed January 18, 1946, now abandoned.

I claim:

1. In a food cutting machine having a hollow container for the food to be treated, a hinged cover for closing the container, a knife located within the container and an electric motor for driving the knife during a food cutting operation, a safety switch assembly comprising a hinge pin for the cover rigidly fixed therein and having a radial cam projection formed thereon, a half-bearing for the pin located on the machine structure adjacent the edge of the hollow container and provided with a clearance formation to accommodate the cam projection on the pin during rotation thereof, a plunger projecting radially through the half-bearing and biased into engagement at its one end with the cam projection to urge the pin off the bearing surface, a switch in the circuit of the electric motor and operatively connected to the plunger so as to be opened when the cover is raised, and a comb detachably secured to the machine structure for co-operating with the knife and having a portion formed to engage the hinge pin and retain it against displacement from the bearing surface of the half-bearing.
2. In a food cutting machine having a hollow container for the food to be treated, a hinged cover for closing the container, a knife located within the container and an electric motor for driving the knife during a food cutting operation, a safety switch assembly comprising a hinge pin rigidly fixed in the cover and having a cam projection formed radially thereon, a bracket mounted on the machine structure adjacent the rim of the container, an upwardly open half-bearing located on the bracket to receive the hinge pin and having a clearance formation for the cam projection, a plunger projecting radially upwards through the half-bearing, means for biasing the plunger into engagement with the cam projection to urge the hinge pin off the bearing surface, a switch controlling the motor circuit and secured to the bracket below the half-bearing for operation by the plunger, and a comb detachably secured to the bracket to co-operate with the knife and formed to engage and retain the pin in the half-bearing.
